UNITED STATES PATENT OFFICE.

CHARLES F. JOHNSTON AND LLOYD A. MARTINELLI, OF SAN FRANCISCO, CALIFORNIA.

CIRCULAR MICROMETER.

Application filed May 11, 1922. Serial No. 560,136.

To all whom it may concern:

Be it known that we, CHARLES F. JOHNSTON and LLOYD A. MARTINELLI, citizens of the United States, and residents of the city and county of San Francisco, State of California, have invented new and useful Improvements in Circular Micrometers, of which the following is a specification.

Our invention has for its object a device 10 adapted to readily and conveniently determine the diameters and widths of circular objects, such as piston rings, pistons, etc. These and other objects which will appear from the specifications, we attain by winding an inexpensive member, preferably a 15 metallic ribbon, about the periphery of the circular piece to be measured, one end of which ribbon is adjustably fixed, and by then drawing the other end of the said ribbon so as to wrap tightly the periphery of the 20 circular piece, the position of the said last named end of said member is then readily read off on a scale, which latter is calibrated for the measurement of diameters or 25 circumferences or both.

The adjustability of the fixed end of the inexpensive member enables instrument errors to be corrected from time to time, or corrections by adjusting the graduations to 30 a master ring or template. The sliding end of the flexible ribbon member may be provided with a vernier for reading fine divisions, and at the end of the said scale we introduce a fixed block or anvil where direct 35 linear measurements may be made, as for example the widths of the rings, discs or other articles.

By referring to the accompanying drawing our invention will be made clear.

40 Fig. 1 is a plan view of our circular micrometer.

Fig. 2 is a side view taken in the direction of the arrow II.

45 Fig. 3 is a side view of Fig. 1 taken in the direction of the arrow III and with the base plate shown partly in section to better illustrate the sliding plate adapted to be removed for the measurement of pistons, pins, or cylinders.

50 Throughout the figures similar numerals refer to identical parts.

A base block or frame is indicated by the 55 numeral 1 on which is fixed a track 2 secured thereto at 3 and 4 respectively. Pivotally mounted at 6 on said track is the plate 5 which carries also the fulcrum 7 and the

adjusting screw 8. The latter is adapted to bear against the side of the track 2. By adjusting the screw 8 the plate 5 is shifted from its full line to its dotted or any intermediate position; thus varying the position of the fulcrum 7. Fixed to the fulcrum 7 is one end of a non-expansile but flexible metallic ribbon strip 9, 10, 11, and we have found material as used in watch and clock springs 60 to be particularly adapted to this, but a ribbon of any other non-extensible material may be employed if preferred. This strip or ribbon of metal is sprung around in the form of a loop as shown in dotted lines at 9. 65 Its other end is carried under the plate 5 and up parallel and against the track 2 as at 10, 11. The end is then fixed to the slide member 12 having a finger engaging end 13. Mounted on the frame 1 or track 2 is fixed 70 finger piece 14 and at other intervals, if desired, there may be attached similar finger members as at 15. On the slide 12 is mounted the vernier 16 adapted to travel across the graduations of the scale 17 fixed to the 75 frame 1. In the full line position of the parts shown in Fig. 1 the flexible strip has been pulled up so that its loop portion 19 tightly grips and compresses the piston ring 18. The ends of the said ring, which normally spring apart, as at 20 are to be drawn together by the loop portion when the final pressure is exerted by the finger members 13, 14. In this final position the slide 12 will occupy its extreme upper position and 80 the zero of the vernier 16 on the scale 17 will then indicate a dimension of 4 as the exact diameter of the piston ring 18. 85

In the dotted position of the slide 12 shown at the bottom of the scale Fig. 1 a 90 diameter of 8" would be embraced by the loop 9.

The adjusting screw 8 is ordinarily employed to correct the instrument by reference to a cast ring or gauge, thus a standard 100 circle 4 inches in diameter may be inserted at any time and unless the zero graduation of the vernier 16 corresponds with line 4 the screw 8 is adjusted until the said graduations do just coincide. This correctly sets 105 the instrument, and it may be then used with great accuracy in measuring other circular pieces between the limits of the scale 17.

In the upper portion of the scale is shown a set of smaller graduations 21 and an anvil 110 22 on the track 2 and a plane end edge 23 on the slide 12 whereby we may measure widths

between the anvil 22 and the edge 23 by drawing together the finger members 13 and 14 as for example the width of the ring 24 between the faces 22 and 23. The graduations at 21 read on the vernier scale 16 and give the exact ring widths. Other finger members as 15 may be established at intervals, so as to make the drawing together of the movable slide by its finger engaging end 13 for different diameters.

It is to be understood that the piston ring joint 20 is to be tightly drawn together to establish the true ring diameter.

In making measurements of circles within the loop it is to be understood that the circular diameter is to bear against the ribbon which in turn bears against the track 2 at the point 30; and again against the fulcrum point 7, thus making two points of contact for the circular periphery. The ring 18 shown in full lines in Fig. 1 is not yet fully drawn up, the joint 20 not being closed, and when so fully drawn up will occupy the position of the dotted lines 31. The lower portion of the base plate 1 we prefer to cut through as on the line 32 so as to permit circular pieces of maximum size to pass clearly through the said opening. A slide plate 33 is provided and is inserted in suitable grooves as 34 bringing the base plate surface flush under the measuring loop at times when the device is employed for measuring thin discs or piston rings, the said slide 33 being withdrawn, however, as by the finger engaging portion 35 when it is desired to measure a piston or other cylindrical object having considerable length and which may then pass freely through the opening 32 in the said plate.

While we have shown but one form of our device, it will be understood that it may be readily built in other forms and the invention embodied in other structures and we desire to be understood as claiming such variations.

We claim:

1. A circular micrometer, comprising a track and slide thereon, a flexible inexten-

sible ribbon having one of its ends fixed to said slide and a body portion forming a loop to embrace an article to be measured and its other end fixed with relation to said track during movement of said slide, a finger member on the slide and another finger member fixed with relation to the track whereby the slide may be moved on the track and the said ribbon thereby caused to embrace said article, a scale on which the movement of the slide is readable, and a base in fixed relation with said track having an opening therethrough adjacent said loop adapted to permit objects to be positioned through the loop and the base.

2. A circular micrometer, comprising a track and slide thereon, a flexible inextensible ribbon having one of its ends fixed to said slide and a body portion forming a loop to embrace an article to be measured and its other end fixed with relation to said track during movement of said slide and means adapted to adjust the position of the slide with reference to the fixture of the ribbon and the track.

3. A circular micrometer, comprising a track and slide thereon, a flexible inextensible ribbon having one of its ends fixed to said slide and a body portion forming a loop to embrace an article to be measured and its other end fixed with relation to said track during movement of said slide, a finger member on the slide and another finger member fixed with relation to the track whereby the slide may be moved on the track and the said ribbon thereby caused to embrace said article, a scale on which the movement of the slide is readable, a base in fixed relation with said track having an opening therethrough adjacent said loop adapted to permit objects to be positioned through the loop and the base, and means adapted to adjust the position of the slide with reference to the fixture of the ribbon and the track.

CHARLES F. JOHNSTON.
LLOYD A. MARTINELLI.
